W. H. FISHER

QUICK ADJUSTABLE WRENCH

Filed April 17, 1925

FIG. 1.

FIG. 2.

FIG. 3.

FIG. 4.

Inventor

William H. Fisher

By *J. Hunt Talbert*
Attorney

UNITED STATES PATENT OFFICE.

WILLIAM H. FISHER, OF ALTOONA, PENNSYLVANIA.

QUICK-ADJUSTABLE WRENCH.

Application filed April 17, 1925. Serial No. 23,925.

To all whom it may concern:

Be it known that I, WILLIAM H. FISHER, a citizen of the United States of America, residing at Altoona, in the county of Blair 5 and State of Pennsylvania, have invented new and useful Improvements in Quick-Adjustable Wrenches, of which the following is a specification.

It is a purpose of the present invention 10 to provide, in a pipe or monkey wrench, an improved construction wherein the jaws may be quickly adjusted, one relative to the other, and when once adjusted, means is provided for retaining a set of teeth carried by the 15 handle of the wrench in engagement with corresponding teeth on the shank of one of the jaws, thereby holding the two jaws in their adjusted positions, said means being so disposed that the more pressure is exerted 20 upon the handle, the tighter the teeth will engage or mesh to insure a firm grip on the pipe to be turned.

It is to be understood that the particulars herein given are in no way limitative and 25 that, while still keeping within the scope of the invention, any desired modifications of detail and desired proportions may be made in the device according to the circumstances.

The invention comprises further features 30 and combinations of parts to be hereinafter set forth, shown in the drawings, and claimed.

In the drawings:

Figure 1 is a view in side elevation of the 35 improved wrench constructed in accordance with the invention;

Fig. 2 is a sectional view through the same, showing the teeth of the handle in mesh with the teeth on the shank of one of 40 the jaws, with a portion of the handle in engagement with means on one of the jaws for retaining the teeth in mesh;

Fig. 3 is a sectional view, showing the teeth on the handle out of mesh with the 45 teeth on the shank of one of the jaws; and

Fig. 4 is a cross-sectional view on line 4-4 of Fig. 2.

Referring to the drawings, 1 designates a sliding movable jaw, the gripping face of 50 which may be plain, as at 2 in Figs. 1 and 2, or toothed, as at 3 in Fig. 3. This jaw has a shank 4 on one face of which a longitudinal groove 5 is formed. The bottom of the groove has teeth 6, and 7 denotes the opposing jaw of the wrench. This jaw is in the

form of a body provided with a passage or opening 8 to receive the shank 4 of the jaw 1.

The jaw 7 has its body toward one edge chambered out or bifurcated, as at 9, for the reception of the end of a handle 10. The received end of the handle on one corner thereof is of arcuate construction which has teeth 11 adapted to mesh at times when holding the jaws relatively fixed and may be disengaged by a lateral movement of the handle, bodily relatively to the jaw 7.

The opposed walls of the chamber or bifurcation of the body of the jaw 7 have opposed registering slots 12 which receive a pivot pin 13 which passes through the toothed end of the handle and has its ends swaged or peened over, not enough to cause any binding between the parts but sufficient to prevent longitudinal movement of the pin. By this means, the parts are pivotally united, rendering the handle capable of pivotal movement when the teeth of the handle and those on the shank 4 are out of mesh.

A portion of the bottom wall of the chamber or bifurcation in the body of the jaw 7 has a curved part 14 and this part merges into an abrupt shoulder 15 at one end. A corner portion 16 opposite the teeth of the handle engages the abrupt shoulder 15 when the two sets of teeth are in mesh, acting to hold the teeth in mesh and maintaining the handle substantially rigid relative to the body of the jaw 7 so that a secure gripping action may be procured on a nut or on a 90 section of pipe, whereby either may be rotated. In the latter instance, the jaw 7 may have teeth 17, as indicated in Fig. 3, just opposite to the teeth 3 of the jaw 1, to further assure a firm grip on a pipe section. 95

To release the teeth, it is necessary to move the handle laterally, maintaining it substantially parallel with the shank 4 of the jaw 1, allowing the pivot pin 13 to move in the elongated openings or slots, as the parts are positioned in Fig. 3. The shank 4 of the jaw 1 is then capable of movement freely through the passage in the jaw 7, thus allowing the jaw 1 to be adjusted to suit any size of pipe section, nut, or the like. 100

The curved part of the bottom of the chamber, when the pivot pin is moved laterally in the slots as in Fig. 3, allows the handle to swing. Furthermore, it is possible to move the handle around a quarter 110

turn or ninety degrees and in this way hold the teeth in mesh, as shown in dotted lines in Fig. 2.

The invention having been set forth,
5 what is claimed is:

1. A quick-adjustable wrench comprising a movable jaw having a toothed shank, an opposing jaw with a passage to movably receive said shank, the opposing jaw being 10 chambered, the opposite walls of the chamber having parallel registering slots, a handle operatively mounted in the chamber with means slideable in the slots to guide the handle in its movement, the handle having 15 teeth meshing with teeth on the shank, a portion of the bottom of the chamber having a curved part emerging into a shoulder, said chambered housed end of the handle having a right-angled part opposite the 20 teeth of the handle and adapted to abut

against said shoulder for holding the teeth in mesh and retaining the handle rigid with the two jaws.

2. A quick-adjustable wrench comprising a movable jaw having a toothed shank, an opposing jaw with a passage to movably receive said shank and provided with a chamber, of which its opposite walls have parallel registering slots, a handle operatively mounted in the chamber and provided with 25 teeth meshing with the teeth on the shank, the chamber having an interior abutting shoulder opposite the teeth of the shank, and means carried by the handle and slideable in the slots, whereby the handle may engage either with the shank or the shoulder for causing a close engagement of the jaws with an object to be turned.

In testimony whereof I affix my signature.

WILLIAM H. FISHER.
